UNITED STATES PATENT OFFICE.

CHARLES R. STEIGER AND JAMES W. KERR, OF SAN FRANCISCO, CAL.

CRUSHING AND GRINDING PAN FOR REDUCING ORES.

SPECIFICATION forming part of Letters Patent No. 237,921, dated February 15, 1881.

Application filed January 21, 1880.

To all whom it may concern:

Be it known that we, CHARLES R. STEIGER and JAMES W. KERR, of the city and county of San Francisco, and State of California, have 5 invented a Continuous Crushing and Grinding Pan for Reducing Ores; and we hereby declare the following to be a full, clear, and exact description thereof.

Our invention relates to certain improvements in the reduction of ores, and in the apparatus employed for that purpose; and it consists in the combination, with what is known as the "Muller" or "Hepburn" pan, of a screen or screens, which are fitted into the side of the 15 pan and provided with controlling-gates, so that the pan may be operated continuously, as may be desired.

Referring to the accompanying drawings for a more complete explanation of our invention, 20 Figure 1 is a view of our improved pan. Fig. 2 is a section of the same.

A is the body of the pan, and B is the bottom, which is made conical or dish-shaped, as shown, and provided with suitable draw-off 25 pipes or openings, C.

Within the pan are fitted peculiarly-shaped dies D, and a muller, E, is driven so as to revolve above these dies by means of a yoke, α , or other connection from the vertical driving- 30 shaft F, which passes up through the center of the pan, as shown. The muller has grooves formed on its lower surface corresponding with those in the dies, and it is suspended by its yoke so as to turn out of contact with the dies, 35 so that its motion, in conjunction with the grooves in its lower face and those in the dies, causes a constant circulation of the pulp beneath the muller up at the outside of the pan, and thence to the center, where it again passes 40 down beneath the muller.

Upon the upper surface of the muller are a series of rollers, G, which are so formed that their peripheries will roll against the inclined side of the bottom B, and they are caused to 45 roll by the motion of the muller.

Into this class of pans the ore is fed from the rock-breaker, and is pulverized by the action of the rollers, as before described; but the operation has hitherto been conducted by

placing successive charges in the pan, and 50 when sufficiently reduced the pulp is drawn off into the amalgamating-pans. One objection to this is the intermittent nature of the operation and the time lost in charging and drawing off, and another is, that much of the 55 pulp is reground after it has become fine enough and is converted into slime, which will not readily amalgamate.

In our invention we form the side A of the pan with one or more openings, H, over 60 which a screen, I, is secured, having a mesh of the proper fineness to permit the escape of all the material as soon as it is sufficiently reduced.

J is a spout or trough, which directs the 65 material into the amalgamating-pans or other receptacles after it has passed through the screen.

In working with our improved pan, the ore is fed continuously into the pan, and as fast 70 as it will pass through the screen it is discharged, so that there need be no intermission in the work, and the screens are not as rapidly worn out, because the ore is not thrown forcibly against them, as it is by the 75 falling of the stamp and the splash in the battery.

If desired, amalgamation may also be carried on within the pan.

A sliding gate, K, is fitted over the opening 80 H, and this may be closed down at any time, so as to prevent the escape of any pulp. When this is done the pan will work separate charges, like ordinary pans, and the ore may then be ground for about three hours, after which the 85 quicksilver is introduced and the amalgamation completed.

By the use of our improved pan we are enabled to work the ore much more perfectly and rapidly, as every particle of ore passes out 90 through the screen as soon as it is reduced to the proper size, and the formation of slimes is prevented, so that the amalgamation will be more perfect.

Having thus described our invention, what 95 we claim as new, and desire to secure by Letters Patent, is—

The combination, with the pan A, provided

with a rotating muller, a series of dies, D, and grinding-rollers G, and an opening, H, in its side, of the screen I, secured in said opening, and adjustable sliding gate K, whereby the ore may be fed continuously into the pan and continuously discharged therefrom or retained in the pan, substantially as described.

In witness whereof we have hereunto set our hands.

CHARLES RUDOLPH STEIGER.
JAMES WATT KERR.
